CLAIM

The ornamental design for a bread slicer, as shown and described.

DESCRIPTION

FIG. 1 is a front, right and top perspective view of a bread slicer showing my new design;

FIG. 2 is a back, left and top perspective view thereof;

FIG. 3 is a front, right and bottom perspective view thereof;

FIG. 4 is a front elevation view thereof;

FIG. 5 is a back elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a perspective view of the bread slicer in folded state; and,

FIG. 11 is an exploded perspective view thereof.

The broken lines depict portions of the bread slicer that form no part of the claimed design.

1 Claim, 11 Drawing Sheets
